UNITED STATES PATENT OFFICE.

JAMES COLE, OF SUPERIOR, WISCONSIN.

MAIL-BAG CRANE.

No. 824,175.

Specification of Letters Patent.

Patented June 26, 1906.

Application filed May 26, 1905. Serial No. 262,893.

To all whom it may concern:

Be it known that I, JAMES COLE, a citizen of the United States, residing at Superior, in the county of Douglas and State of Wisconsin, have invented certain new and useful Improvements in Mail-Bag Cranes, of which the following is a specification, reference being had therein to the accompanying drawings.

The invention relates to mail-bag cranes, and has for one object the obtaining of a construction adapted for delivering the mail-bags to trains traveling on different tracks. It is a further object to obtain a simple construction the mechanism of which is protected from the weather.

With these objects in view the invention consists in certain novel features of construction, as hereinafter set forth.

In the drawings, Figure 1 is a sectional elevation of the mail-bag crane. Fig. 2 is a plan view illustrating its arrangement in relation to a double-track railroad. Fig. 3 is a perspective view of the coöperating portions of the mechanism within the base of the crane.

With mail-bag cranes of the type to which my invention belongs the mail-bags are suspended from the arms of the crane in such relation to the track over which the train passes that the center of the bag is struck by a projecting arm from the car and is doubled over the same. It is necessary that the laterally-projecting arms on the crane should extend into close proximity to the car, and it is very important that these arms should be removed from this position as soon as the bag is delivered, as otherwise there is great danger of striking any projecting object on the train. With the present construction the withdrawal of the arms is effected, first, by a construction which causes them to automatically swing in a vertical plane when relieved of the weight of the mail-bag, and, second, by a construction which causes the rotation of the post on which said arms are mounted to carry the latter from a plane at right angles to the track to a plane parallel therewith. Thus the withdrawal of the arms is doubly insured and a failure in operation of one portion of the mechanism cannot result disastrously by reason of the operation of the other portion of the mechanism.

A is the vertical post of the crane, which is mounted in a base-section B, so as to be capable of rotation. This base B is hollow and forms an inclosing casing for a member C, secured to the lower end of the post A, and a co-

operating stationary member D, secured in position, as by fastening to the railway-tie E. The member D is so fashioned as to afford a raised support for the member C in one position and also to effect the partial rotation of said member C when disengaged from said raised support. As shown in Fig. 3, this is accomplished by providing two upwardly-projecting tapering lugs a a' and an intermediate V-shaped recess b. The upper ends of the lugs a a' have a limited flattened area c, upon which the member C may rest, and from the edge of this flattened area the inclined face d forms a cam for revolving the member C. The member C is preferably of the wedge-shaped form illustrated, having a sharpened or narrow edge e, adapted to rest upon the flattened portion c, and the tapering sides f, which coöperate with the inclines d for effecting the rotation when disengaged from the flattened face. Thus a slight rotary movement of the post A will be sufficient to disengage the edge e from the face c, upon which the downward movement of the post A and member C will cause a rotation thereof through substantially ninety degrees.

For raising the post A so as to engage the member C with the raised flattened faces c on the member D a lever G is pivotally connected at g to the post. This lever is fulcrumed by resting upon an annular flange h at the upper end of the base B, and by depressing the outer end of the lever the post will be elevated. To prevent danger of rain or snow accumulating in the annular recess between the flange h and the post A, a cap H is secured to the post above the lever, and drain-apertures i are arranged to permit the escape of any water caught within the flange.

The mail-bag to be delivered is held by a pair of laterally-projecting arms J and K, which are pivotally connected to the post A. The upper arm J has a rearward extension to form, in effect, a lever of the first class, and this rearwardly-projecting end of said arm is connected by a link L to a pivot j on the arm K between its pivot k on the post and its outer end. The arm K is counterweighted, as by the block M, secured thereto, so that when free it will overbalance the lever J and will fall into the position indicated in dotted lines. In so doing the link L will draw downward the rearward extension of the arm J, swinging its forward end upward into the dotted position. Thus both arms when released will assume a position in substantial parallel-

ism to the post A and will therefore be withdrawn from proximity to the moving train.

- As has been stated, it is one object of the invention to use a single crane for delivering 5 mail-bags to trains traveling on different tracks. As illustrated in Fig. 2, O and P are a pair of parallel tracks, centrally between which the crane is mounted, as indicated. The arms J and K are of such a length that 10 they will extend into proximity to a train on either track when arranged as indicated in full lines in Fig. 1, and the operation of delivering the mail-bags is as follows: The mail-bag is first engaged with the arms J and 15 K and secured thereto, as by the loops l, which engage the ends of said arms. The operator then depresses the lever G, raising the post A, and by then swinging the lever and sliding it upon the annular flange h the 20 post A may be partially rotated until the arms J and K project at right angles to the track. In this position the sharpened lower edge e of the member C will rest upon the flat area c of the member D. When the project- 25 ing arm on the car strikes the center of the bag, it will cause a sufficient turning of the post to disengage the edge e of the member C from the flat faces c of the member D, where- 30 upon the inclined faces f d will cause a rotation of the post A through a quarter of a revolution. This will swing the arms J and K into a plane parallel to the track, and during the swinging movement the bag will be dis- 35 engaged from the arms. Upon the disen- gagement of the bag from the arms J and K they will be respectively swung upward and downward by the actuation of the weight M and by means of the connecting-link L. Thus the arms will be arranged in parallelism with 40 the post A.
- It is obvious that the crane may be used to 45 deliver bags to trains passing on either of the tracks and may be changed from operative relation to one track to a corresponding position in relation to the other track by merely rotating the shaft A through a one-half revolution. In order to indicate to the engineer of the approaching train the condition of the crane, a signal-lamp Q is preferably mounted 50 on top of the post A, and it will display different signal-colors, according to the position in which said post is turned

What I claim as my invention is—

1. A mail-bag crane comprising a post, bag-holding arms projecting laterally therefrom, means for automatically withdrawing said arms when the bag is disengaged therefrom, and means for reversing the direction in which said arms project, whereby they may be alternatively used in connection with 55 trains traveling on adjacent tracks.

2. In a mail-bag crane, a base, a vertical post revolvably secured in said base, a foot on said post arranged within a chamber in said base, and a supporting member for said foot 60 having a bearing of limited area therefor, and an adjacent incline for rotating said post when disengaged from said bearing.

3. In a mail-bag crane, the combination of a chambered base, a vertical post revolvably secured in said base, a foot for said post within the chamber in the base and having a narrow under face, and a support for said foot within said chamber comprising upwardly-tapering lugs having a limited flattened area 75 at their upper ends for supporting the narrow under face of said foot, whereby the descent of said foot when disengaged from said flattened area will cause a partial rotation of the post. 80

4. A mail-bag crane comprising a revolv- 85 able post, a foot at the lower end thereof, a support for said foot having an inclined face for causing a partial rotation of the foot and post, a base in which said post is journaled, a lever pivotally connected to said post, and an annular flange on said base forming a ful- 90 crum for said lever in different points of rotary adjustment about the axis of said post.

5. A mail-bag crane comprising the base B, 95 the vertical post journaled therein, the foot C at the lower end of said post, and the coöperating cam-supporting member D, the annular flange h at the upper end of said base and the lever G pivoted to said post and fulcrumed upon said flange, substantially as and for the purpose set forth.

In testimony whereof I affix my signature in presence of two witnesses.

JAMES COLE.
